US0D1051966S

(12) **United States Design Patent** (10) **Patent No.:** **US D1,051,966 S**
(45) **Date of Patent:** **** Nov. 19, 2024**

(54) **ROBOTIC SURGICAL ARM CART**

(71) Applicant: **Covidien LP**, Mansfield, MA (US)

(72) Inventors: **Jaimeen V. Kapadia**, Cambridge, MA (US); **Shane Reardon**, Branford, CT (US)

(73) Assignee: **Covidien LP**, Mansfield, MA (US)

(**) Term: **15 Years**

(21) Appl. No.: **29/829,813**

(22) Filed: **Mar. 8, 2022**

(57) **CLAIM**

The ornamental design for a robotic surgical arm cart, substantially as shown and described.

DESCRIPTION

FIG. 1 is a perspective view of a robotic surgical arm cart; FIG. 2 is a top plan view, thereof; FIG. 3 is a front elevational view, thereof; FIG. 4 is a back elevational view, thereof; FIG. 5 is a left side view, thereof; and, FIG. 6 is a right side view, thereof.

The broken lines in the drawings depict portions of the robotic surgical cart that form no part of the claimed design.
